UNITED STATES PATENT OFFICE

136,980

DESIGN FOR A CASE FOR A LIGHTER OR THE LIKE

Darold B. Hickman, North Attleboro, Mass., assignor to Evans Case Company, North Attleboro, Mass., a corporation of Massachusetts

Application September 11, 1943, Serial No. 111,100

Term of patent 14 years

To all whom it may concern:

Be it known that I, Darold B. Hickman, a citizen of the United States, residing at North Attleboro, county of Bristol, and State of Massachusetts, have invented a new, original, and ornamental Design for a Case for a Lighter or the like, of which the following is a specification, reference being had to the accompanying drawing, forming a part thereof.

In the accompanying drawing:

The side opposite that shown in Fig. 3 is substantially the same as the side illustrated.

The dominant features of the invention reside in the portions shown in full lines.

I claim:

The ornamental design for a case for a lighter or the like, substantially as shown and described.

DAROLD B. HICKMAN.
